UNITED STATES PATENT OFFICE.

THEODORE W. FOSTER, OF PROVIDENCE, RHODE ISLAND.

DESIGN FOR A BRUSH OR SIMILAR ARTICLE.

41,852.

Specification for Design.

Patented Oct. 24, 1911.

Application filed March 31, 1911. Serial No. 618,254. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for a Brush or Similar Article, reference being had to the accompanying drawing.

Figure 1 is a side view of a brush, showing my design. Fig. 2 is an end view of the same.

I claim—

The ornamental design for a brush or similar article, as shown.

THEODORE W. FOSTER.

Witnesses:

ADA E. HAGERTY,
J. A. MILLER.
